UNITED STATES PATENT OFFICE.

BONIFACE A. GRASBERGER, OF RICHMOND, VIRGINIA.

DESIGN FOR A SINGLE-SERVICE WOODEN SPOON.

53,588.

Specification for Design.

Patented July 15, 1919.

Application filed January 30, 1919. Serial No. 274,152. Term of patent 14 years.

To all whom it may concern:

Be it known that I, BONIFACE A. GRASBERGER, a citizen of the United States of America, residing at Richmond, in the county of Henrico and State of Virginia, have invented a new, original, and ornamental Design for a Single-Service Wooden Spoon, of which the following is a specification, reference being had to the accompanying drawing, forming part thereof.

In the drawing,

Figure 1 is a plan view of a spoon showing my new design;

Fig. 2 is an edge view of the same.

I claim:

The ornamental design for a single service wooden spoon, as shown.

BONIFACE A. GRASBERGER. [L. S.]
